UNITED STATES PATENT OFFICE.

MATHEW E. ROTHBERG AND ALFRED ERNST, OF CLEVELAND, OHIO.

COKE-OVEN.

No. 833,340.

Specification of Letters Patent.

Patented Oct. 16, 1906.

Application filed March 10, 1906. Serial No. 305,351.

To all whom it may concern:

Be it known that we, MATHEW E. ROTHBERG and ALFRED ERNST, citizens of the United States, and residents of Cleveland, in the county of Cuyahoga and State of Ohio, have made a certain new and useful Invention in Coke-Ovens; and we declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a section on the line 1 1, Fig. 2, the ovens being shown in full lines. Fig. 2 is a section on the line 2 2, Fig. 1. Fig. 3 represents vertical longitudinal half-sections taken, respectively, through the coking-chamber A and through the heating-flues in the partition-walls. Fig. 4 is a plan view of the stack end of the battery of ovens. Fig. 5 is a plan view, partly in section, illustrating the modification of our invention. Fig. 6 is a section on the line 6 6, Fig. 5.

The invention relates to coke-ovens of the regenerative type, having for its object the provision of a continuous supply of heated air to the combustion-chambers of the ovens by reversing the flow of waste gases used for heating the regenerators and the flow of cold air outside of the ovens proper, thus preventing injurious shocks to the brickwork of the ovens, which cause the development of cracks in the same and ultimately lead to loss of gas.

With this object in view the invention consists in the novel construction and combinations of parts, as hereinafter set forth.

In the accompanying drawings, illustrating the invention, the letter *z* designates the foundation of a battery of ovens *a b c d*.

F' is the main flue, extending longitudinally of the battery of ovens in the foundation thereof and having openings *A* in its top wall communicating with the off-gas flues of the ovens. This flue *F'* extends beyond the battery of ovens at one end thereof, where it is provided with a butterfly-valve *V'*, controlling the communication of the flue *F'*, with flanking regenerator-chambers *R' R²* at each side of the same. These regenerator-chambers project beyond the ovens at each end and beyond the flue *F'* at one end into communication with the stack *S*, the opening to which is controlled by a butterfly-valve

V⁴, which cuts off one chamber from communication with the stack, while it throws the other chamber into communication therewith in an alternate manner.

B⁵ is a fan located outside of the oven-battery between the stack *S* and the termination of main flue *F'* at one end of the ovens and which, through the passage *B⁶*, communicating with flues *H* in the floors of the ovens, establishes a circulation of air, blowing the same through the medium of butterfly-valve *V²* into one end of the regenerator-chambers *R' R²* alternately and through the medium of a similar valve *V³* controlling the communication of the other ends of said chambers with hot-air flues *F² F³* alternately from said chambers into the hot-air flues, which are arranged longitudinally in the oven-foundation laterally of the regenerator-chambers, and have connection by openings *C D* with the combustion-chambers of the ovens, where the hot air meets the gas-supply.

The oven to which our invention is shown applied is that of the patent granted to M. E. Rothberg, No. 804,053, dated November 7, 1905, in which *D* is the hot-air inlet-chamber under the reverting heating-flues *B' B² B³ B⁴* in the side walls of the oven-chambers. Each chamber *D* communicates by openings *N* with the combustion-chamber *C* of the oven *A'*, located under the same, along which the heated air passes, being at the same time mixed with the gas from the burner *X*, branching from the gas-feed pipe *W*. Near the center of the oven the heated air and gas pass through the short transverse flue *B⁷* to the series of heating-flues *B' B² B³ B⁴*, and therefrom the products of combustion pass down through the vertical flue *F* to the main off-gas flue *F'*, leading to the stack.

In Figs. 5 and 6 of the drawings is shown a modification of our invention in which but two valves *Y* and *Y'* are employed to effect the same result.

Having thus described our invention, what we claim as new, and desire to secure by Letters Patent, is—

1. In an oven, having heating-flues in its walls, and a combustion-chamber in connection therewith, means for continuously withdrawing the waste gases of combustion in the same direction from said heating-flues, means located beneath the oven for continuously supplying air in the same direction to said combustion-chamber, and means lo-

cated beneath the oven and disposed at right angles to the oven-chamber for continuously heating the air-supply through the waste gases of combustion.

5. 2. In a coke-oven having reverting heating-flues in its side walls and a combustion-chamber in connection therewith located under the coking-chamber, means for continuously withdrawing the waste gases of combustion in the same direction from said heating-flues, means located beneath the oven for continuously supplying air in the same direction to said combustion-chamber, and means located beneath the oven and disposed at right angles to the oven-chamber for continuously heating the air-supply through said waste gases.

20. 3. In an oven having a combustion-chamber, a pair of regenerator-chambers, air-supply passages to the combustion-chamber of the oven, means for conducting a supply of air through one of said regenerator-chambers and thence through both air-supply passages, means for simultaneously conducting the waste gases of combustion through the other of said chambers, and means for changing the flow of air and waste gases from each of said chambers to the other chamber.

30. 4. In ovens having combustion-chambers, a pair of regenerator-chambers, air-supply passages to the combustion-chambers of the ovens, means for conducting a supply of air through one of said regenerator-chambers, and thence through both air-supply passages, and means for alternating the flow of air through the regenerator-chambers.

40. 5. A coke-oven having heating-flues in its walls provided with combustion-chambers, air-supply passages to said combustion-chambers, horizontal regenerating-chambers disposed at right angles to the oven-chamber and respectively in connection with said air-supply passages and with said combustion-chambers, means for continuously withdrawing the waste products of combustion in the same direction from said heating-flues alternately through said regenerator-chambers to the stack, means for continuously 45 conducting air in the same direction alternately through the regenerating-chambers to the combustion-chambers, and means for alternating the flow of air and waste gases through the regenerating-chambers.

55. 6. In coke-ovens, the combination of a central main flue having communication with the off-gas flues of the ovens, lateral regenerator-chambers parallel to and having communication with said central flue at one end, a stack-flue having communication with said regenerator-chambers at the other end of the same, means for deflecting the flow of gases through said main flue from one of said chambers to the other, and means for

controlling the communication of the re- 65 generator-chambers with the stack-flue.

7. In coke-ovens, the combination of a central main flue having communication with the off-gas flues of the ovens, lateral regenerator-chambers having communication with said central flue at one end, a stack-flue having communication with said regenerator-chambers at the other end of the same, lateral hot-air flues having communication with said regenerator-chambers at one end thereof, a fan having an air supply and an exhaust communication with said chambers at the other end of the same, means for deflecting the flow of gases through said main flue from one of said chambers to the other and for controlling the communication of said chambers with the hot-air flues, and means for deflecting the exhaust from said fan from one of said chambers to the other and for controlling the communication of said chambers with the stack-flue.

25. 8. In coke-ovens, the combination of regenerator-chambers, lateral hot-air flues having communication with said chambers at one end thereof, a fan having an air supply 90 and an exhaust communication with said chambers at the other end of the same, means for deflecting the exhaust from said fan from one of said chambers to the other, and means for controlling the communication of said chambers with the hot-air flues.

35. 9. In coke-ovens, the combination of a central main flue having communication with the off-gas flues of the ovens, lateral regenerator-chambers parallel to and having communication with said central flue at one end, a stack-flue having communication with said chambers at the other end of the same, valved means located outside the ovens for controlling the communication of said main flue with said chambers, and valved means located outside the ovens for controlling the communication of said chambers with the stack-flue.

45. 10. In coke-ovens having off-gas flues, the combination of a central main flue having communication with said off-gas flues, lateral regenerator-chambers having communication with said central flue at one end thereof, a stack-flue having communication with said regenerator-chambers at the other end of the same, lateral hot-air flues having communication with said regenerator-chambers at one end thereof, a fan having an air supply and an exhaust communication with said chambers at the other end of the same, valved means located outside the ovens for deflecting the flow of gases through said main flue from one of said chambers to the other, and for controlling the communication of said chambers with the hot-air flues, and valved means located outside the ovens for deflecting the exhaust from said fan from one of

said chambers to the other, and for controlling the communication of said chambers with the stack-flue.

11. In coke-ovens, the combination of regenerator-chambers, lateral hot-air flues having communication with said chambers at one end thereof, a fan having an air supply and an exhaust communication with said chambers at the other end of the same, valved means located outside the ovens for controlling the exhaust communication of said fan with said chambers, and valved means located outside the ovens for controlling the communication of said chambers with the hot-air flue.

12. In an oven having a combustion-chamber, a pair of regenerator-chambers, air-sup-

ply passages to the combustion-chamber of the oven, means for conducting a supply of air through one of said regenerator-chambers and thence through both air-supply passages, means for simultaneously conducting the waste gases of combustion through the other of said chambers, and valved means located outside the oven for changing the flow of air and waste gases from each of said chambers to the other chamber.

In testimony whereof we affix our signatures in presence of two witnesses.
